INVENTOR.
Fred C. Arey,
BY *Wm. G. Freudenrich*,
ATTORNEY.

UNITED STATES PATENT OFFICE

FRED C. AREY, OF OAK PARK, ILLINOIS, ASSIGNOR TO JOHN W. GLEASON, FRANK W. BORA, WILLIAM F. FREUDENREICH, FREDERICK H. CHETLAIN, AND SAID FRED C. AREY AS TRUSTEES, FOR U. S. LATH AND MACHINERY CO.

EXPANDED METAL LATH

Application filed July 28, 1927. Serial No. 208,916.

The present invention relates to expanded metal lath consisting of sections or panels of diamond mesh alternating with longitudinal ribs; and has for its object to produce a construction in which all of the longitudinals shall have their flat faces parallel with each other and lying at an angle to the plane of the sheet in order that the plaster may be uniformly applied by sweeping the same transversely across the sheet in one direction.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a plan view of the slotted unexpanded sheet from which my improved expanded metal is made; Fig. 2 is a plan view of a fragment of the finished product; and Fig. 3 is a section taken approximately on line 3—3 of Fig. 2.

Referring to Figure 1 of the drawings, A represents a metal sheet divided into slotted sections alternating with narrow solid sections adapted to form longitudinal ribs. The slits are made in the manner commonly employed in the manufacture of diamond mesh, namely in parallel broken lines arranged in staggered relation to each other. The slotted sections are divided into two groups B and C alternating with each other and separated from each other by a narrow longitudinal unslit portion D. The slits in the two groups of slotted sections are oppositely inclined. In expanding the sheet I cause the slotted portions to turn on edge to form ribs 1 lying at an angle to the plane of the sheet and parallel with the longitudinal strands 2 of the diamond mesh. The ribs and the longitudinal strands are connected by the transverse strands 3 of the diamond mesh; these transverse strands extending from the front edge of one rib to the rear edge of the opposite rib.

When plaster is swept across the face of the lath, say from the bottom toward the top as viewed in Fig. 3, it will be seen that it is met by the broad faces of all of the longi-

tudinals, namely the longitudinal strands of the mesh and the longitudinal ribs, instead of meeting some edges and some broad flat faces as is usually the case.

It will thus be seen that my improved sheet may be said to be made up of expanded sections, alternating with solid sections, each pair of consecutive expanded sections being symmetrical with respect to a plane lying approximately parallel to the lengths of the transverse strands and cutting through the metal of the intervening solid section.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A sheet of expanded metal comprising expanded sections alternating with longitudinal solid sections, said expanded sections consisting of transverse strands and longitudinal strands the two expanded sections lying on opposite sides of one of said solid sections being symmetrically disposed with respect to the latter, said solid sections and said longitudinal strands having their broad faces lying parallel to each other and at an angle to the plane of the sheet, and each portion of the sheet made up of two expanded sections and an interposed solid section being symmetrical with respect to a plane lying approximately parallel with the lengths of the transverse strands and cutting through the metal of said solid section.

2. A sheet of expanded metal comprising expanded sections alternating with longitudinal flat rib sections, said expanded sections consisting of transverse strands and longitudinal strands, said rib sections and said longitudinal strands having their flat faces lying parallel to each other and at an angle to the plane of the sheet, the transverse strands in the expanded section on one side of a flat rib being stepped upwardly from the preceding transverse strands as the distance from said rib increases, while the trans-

verse strands on the opposite side of the rib are stepped downwardly from the preceding strands as the distance from said rib increases, and each portion of the sheet made
5 up of two expanded sections and an interposed solid section being symmetrical with respect to a plane lying approximately parallel with the lengths of the transverse strands and cutting through the metal of said
10 solid section.

3. A sheet of expanded metal comprising expanded sections alternating with longitudinal flat rib sections, said expanded sections consisting of diamond mesh certain of whose
15 strands form longitudinals, the flat faces of the rib sections and of all the longitudinals lying parallel to each other and at an angle to the plane of the sheet, and each portion of the sheet made up of two expanded sections
20 and an interposed solid section being symmetrical with respect to a plane lying approximately parallel with the lengths of the transverse strands and cutting through the metal of said solid section.

25 4. A sheet of expanded metal comprising expanded sections alternating with longitudinal flat rib sections, said expanded sections consisting of diamond mesh certain of whose strands form longitudinals, the flat
30 faces of the rib sections and of all the longitudinals lying parallel to each other and at an angle to the plane of the sheet, the elements of two of said expanded sections on opposite sides of one of the ribs being symmetrically
35 disposed with respect to a plane extending through such rib between and parallel with such sections.

In testimony whereof, I sign this specification.

40 FRED C. AREY.
